(57) **CLAIM**

We claim the ornamental design for a battery charger pedestal, as shown and described.

DESCRIPTION

FIG. 1 is a front, left side perspective view of a battery charger pedestal, showing our new design;

FIG. 2 is a front, right perspective view thereof;

FIG. 3 is a front elevational view thereof, the rear elevational view being identical thereto;

FIG. 4 is a left elevational view thereof, the right elevational view being identical thereto;

FIG. 5 is a top plan view thereof; and,

FIG. 6 is a bottom plan view thereof.

The broken lines in the drawings depict portions of the battery charger pedestal that form no part of the claimed design.
